(57) **CLAIM**

The ornamental design for a wine stopper, as shown and described.

DESCRIPTION

FIG. 1 is a perspective view of a wine stopper showing the new design.

FIG. 2 is an installed perspective view of the wine stopper of FIG. 1 in combination with a stand and a wine dispenser and preserver.

FIG. 3 is an exploded perspective view of the wine stopper of FIG. 1 in combination with the stand and the wine dispenser and preserver.

FIG. 4 is a front view of the wine stopper of FIG. 1.

FIG. 5 is a rear view of the wine stopper of FIG. 1.

FIG. 6 is a side view of the wine stopper of FIG. 1.

FIG. 7 is an opposite side view the wine stopper of FIG. 1.

FIG. 8 is a top view the wine stopper of FIG. 1; and,

FIG. 9 is a bottom view the wine stopper of FIG. 1.

The dashed lines in the drawings represent environmental structure that forms no part of the claimed design.
